UNITED STATES PATENT OFFICE.

LAWRENCE DINKELSPIEL, OF WEST NEW YORK, NEW JERSEY, ASSIGNOR TO HARNAPP, DINKELSPIEL & CO. INC., A CORPORATION OF NEW YORK.

DESIGN FOR LACE TRIMMING FOR DOILY OR SIMILAR ARTICLE.

Application filed January 7, 1926. Serial No. 15,990. Term of patent 3½ years.

To all whom it may concern:

Be it known that I, LAWRENCE DINKELSPIEL, a citizen of the United States, residing at West New York, in the county of Hudson and State of New Jersey, have invented a new, original, and ornamental Design for Lace Trimming for Doily or Similar Article, of which the following is a specification, reference being had to the accompanying drawing, forming part thereof.

The figure is a plan view of a lace trimming for doily or similar article, showing my new design.

The design is repeated throughout, and the two ends are identical, as shown by the one illustrated.

I claim:

The ornamental design for lace trimming for doily or similar article, as shown.

LAWRENCE DINKELSPIEL.
